HYDRAULIC LINE SPOOLER

Samuel T. Peppard, Fullerton, Calif., assignor of
one-half to Leslie Claude Howe, Orange, Calif.

Application August 31, 1938, Serial No. 227,736

9 Claims. (Cl. 242—157)

My invention relates to a line spooler of the hydraulic type particularly designed to maintain a pressure on a cable as it is wound on and off a drum such as used in oil well draw works 5 or the like. In these types of hydraulic line spoolers a pressure is maintained by a hydraulic fluid on travelling pulleys or rollers which contact the cable and thus line the cable as it is wound on the drum in close and snug positions 10 as to the different convolutions on the drum.

An object and feature of my present invention of the hydraulic line spooler relates in part to the control of the pressure on hydraulic fluid as it is transferred from one end to the other 15 of a hydraulic cylinder through the medium of the pulleys or rollers engaging the cable being thrust from side to side due to the winding of the cable on or off the drum. This control pressure develops a thrust sidewise on the cable to 20 force the convolutions into close contact. A further feature of my invention is in the construction of the by-pass control with a valve reacting against springs which thus regulate the opening or passage for the liquid as it is transferred from one end to the other or a cylinder 25 by a moving piston. In this connection a more detailed object and feature of my invention is constructing the by-pass control in the form of a small cylinder with a plug valve therein, such 30 plug valve operating through a port from one side to the other and travelling against the reaction of a spring on each side of the valve, thus by using springs of the desired strength, the force required to displace the valve may be made 35 of a suitable value and thus control the by-pass of the liquid.

Another object and feature of my invention relates to the manner of inter-linking the pulleys or rollers which engage the cable and the 40 piston of the hydraulic cylinder to reciprocate such piston and thus displace the liquid. An object and feature of this connection is the employment of a long lever which has the pulleys or rollers pivotally mounted on its outer end, 45 such pulleys forming a travel guide for the cable. A pin or stud fixedly mounted on the lever and which thus swings in an arc operates an anti-friction bearing operating vertically in a travelling carriage, this latter being connected 50 to a reciprocating rod, thence by means of opposite cross heads connected to such rod and a double piston rod connected to the cross heads, I reciprocate the piston in the hydraulic cylinder causing the by-pass of the liquid from one end 55 of the cylinder to the other. Another feature

of my invention relates to the pulley or roller mount for engaging the cable in which a rod is slidably mounted on the outer end of the lever for the purpose of spacing the pulleys or cable rollers variable distances from the lever as the windings build up or reduce in diameter 5 on the drum. Another feature relates to the pulley engagement with the cable including a pair of rollers engaging one side of the cable and a single adjustable roller engaging the opposite side, thence by adjusting the single roller the desired pressure may be exerted on the cable between the group of three rollers.

My invention is illustrated in the accompanying drawings in which:

Fig. 1 is a front elevation taken in the direction of the arrow 1 of Fig. 2.

Fig. 2 is a vertical transverse section on the line 2—2 of Fig. 1 in the direction of the arrows.

Fig. 3 is an end elevation taken in the direction of the arrow 3 of Fig. 1 illustrating the cross head at the end of the cylinder, the upper portion of the construction being omitted.

Fig. 4 is a vertical section on the line 4—4 25 of Fig. 2 in the direction of the arrows showing the back elevation of the pulley or roller mount forming the travel guide of the cable.

Fig. 5 is a detail section on the line 5—5 of Fig. 4.

Fig. 6 is a vertical longitudinal section of the main cylinder taken on the line 6—6 of Fig. 2.

Fig. 7 is a vertical transverse section through the main cylinder on the line 7—7 of Fig. 6 in the direction of the arrows.

Fig. 8 is a longitudinal vertical section through the by-pass control valve assembly and may be considered as taken on the section line 8—8 of Fig. 9 in the direction of the arrows.

Fig. 9 is a vertical transverse section on the line 9—9 of Fig. 8 in the direction of the arrows.

Fig. 10 is a vertical section on the line 10—10 of Fig. 2 or 11 showing the guide for the travelling carriage connecting the moving rod and the pivoted lever.

Fig. 11 is a horizontal section of Fig. 10 on the line 11—11 taken in the direction of the arrows.

Fig. 12 is a detail section on the line 12—12 of Fig. 2 in the direction of the arrows showing 50 a friction brake clamp.

In my invention I employ a frame structure designated 11. This has an angle member 12 with a horizontal or base flange 13 and a vertical flange 14. Welded to these flanges are two 55

end plates 15, each being similar and having an opening therethrough. Each plate has an upward extension 16 for a purpose hereunder designated. Each plate 15 has a large opening 17 for the main cylinder assembly 20. This assembly 5 includes a cylinder 21 threaded at its opposite ends 22 and on each end of which there is a closure head 23. Each head has a recess 24 in which is fitted packing 25 held in place by a packing gland 26. The heads thus clamp the cylinder 21 in the frame. The piston 30 is shown as of a double cup type having cup leathers 31 facing in opposite directions and is secured to about the center 32 of the double piston rod 33, such piston rod passing through the heads, the packing and the packing gland. Secured to the outer ends of the piston rod there are cross heads 35. These cross heads are in the form of bars 36 clamped together by rivets or screws 37. Thus, by their lower jaws 38 engaging the ends of the piston rods, their upper jaws are clamped to a long reciprocating or complementary rod 40. A positive movement given to the rod 40 which operates through perforations in the upper end 16 of the end plates 15 and over roller guides 41 is secured to the plates 15, is operative through the medium of the cross heads 35 of reciprocating the piston rod 33 and thus the single piston 30.

30 The positive movement is communicated to the reciprocating rod 40 by a lever assembly 50 which develops an oscillating movement due to the winding of the cable on and off of a drum. This assembly employs a long lever arm 51 pivoted at its lower end to a pintle bolt 53 secured to a lug 54 on the base flange 13 of the angle 12. This lever has a straight vertical section 55, an outward bend 56 and a vertical section 57 with a guide eye 58 at the top.

40 The roller or pulley mount 60 has a supporting pin 61 which is slidable in the eye 58, such eye having its axis transverse to the axis of the main cylinder 21. There is a stop head 62 at the inner end of the pin and a somewhat triangular shaped plate 63 secured to its outer end by means of the collar 64 and set screw 65. A friction brake clamp assembly 160 employs a bracket 161 attached to the side of the eye 58. This has two opposite brake shoes 162 attached to the bracket 45 and extending in opposite directions around the supporting pin 61. A lining 163 fits inside of the shoes. These are regulated as to adjustment by the shoes having projecting tongues 164 with a clamping bolt 165 extending therethrough and also through an eye 166 extending from the eye 58, thence by means of springs 167 a resilient pressure is maintained against the brake shoes and this may be regulated by tightening or loosening the bolt. This friction restrains the pin 61 from rotation and also from longitudinal reciprocation as to the eye 58, however the brake or clamping action is not sufficiently tight to prevent the necessary movement.

50 On the plate 63 there are mounted three rollers, 65 67 and 68 being located on one side and the larger roller 69 on the opposite, therefore these rollers are in effect mounted on the corners of the triangular plate 63. The particular attachment of the rollers is illustrated in Fig. 5 in which the headed axle bolt 70 and provided with a shoulder 71 is clamped to the plate 63 by a nut 72 threaded on the end. A washer 73 bears against the plate. As to the roller 69, there is provided a slot 74 arranged radially to permit adjustment 70 of this roller. The other rollers 67 and 68 are

located in a fixed position. Each of the rollers has an annular groove 75 to accommodate the cable 76. It will be apparent that as the rollers 67 and 68 are not adjustable they may be riveted to the plate 63.

5 By having the larger roller 69 adjustable, the cable may be readily threaded or fitted through the assembly of rollers or pulleys and then the roller 69 adjusted to have an operating engagement with the cables. Therefore as the cables 10 lead to one side or the other, that is, oscillate between the left and right dotted line position through the full line position of Fig. 1, the pulley mount may oscillate on the pin 61 in the eye 58. This pin also has a sliding motion in the eye to 15 accommodate the build up of the cable on drum, that is, the winding having different effective diameters. This motion is illustrated by the full and dotted line positions of the pulley mount 60 in Fig. 2.

20 Motion is communicated by the lever assembly 51 through the medium of a travelling carriage designated by the assembly numeral 80, note Figs. 10 and 11. This employs a sleeve 81 fitted on the rod 40 and clamped tight thereto, preferably at the central position by a set pin 82. On the front of the sleeve there is a vertical channel structure 85. This has a back plate 86, two vertical sides 87, inturned flanges 88, thus forming a pair of opposite vertical channels 89. The back 30 plate also has a vertical recess 90 defined by the vertical straight line edges 91. A pivot assembly 95 employs a pivot bolt 96 which extends through a perforation 97 in the section 55 of the lever 51 and has a nut 98 threaded on its outer end. The inner end of the bolt has a head 99 operating in the vertical channel 90. An anti-friction bearing 105 employs an inner race 106 having a tight fit on the bolt 96, an outer race 107 which engages in the vertical channels 89 defined by the back plate 86, the sides 87 and the flanges 88. Anti-friction balls 108 are intermediate these races. A sleeve 109 is fitted between the inner race and the section 55 of the lever 51.

35 In view of the fact that the bolt 96 moves through an arc indicated by the dotted lines 110, Fig. 1, and the sleeve 81 of the carriage assembly 80 has a straight line motion, it is apparent that the head 99 of the bolt has a vertical motion relative to the vertical channel 90 formed as a recess, however, the frictional resistance to this vertical motion is overcome by the anti-friction bearing 105 which operates in the larger channels 89. There is a slight clearance of the outer periphery of the outer race of the bearing between the inside face of the sides 87 of the channel 89 so that in one direction of movement there will be a pressure of the anti-friction bearing against one of the sides 87 and in the motion in the opposite direction, the pressure will be against the opposite side. This allows for the slight vertical rolling motion. The head 99 has no contact with the channel 90, therefore by this construction, as the long lever 51 is forced in its oscillating motion from one side to the other through the medium of the collar 81 and the carriage assembly 80, the rod 40 and the assembly of the cross heads 35 and piston 30 is caused to reciprocate in the cylinder 21. The controllable pressure for this reciprocation is by means of a by-pass assembly 115. At each end of the cylinder 21 and inside of the plates 15 there are two pipes 116, note Figs. 1 and 6, these being outside of the stroke of the piston so that they are never covered by the cups of the piston. Horizontal pipes 117 are connected to the ver- 40

45 50 55 60 65 70 75 80 85 90 95 100 105 110 115 120

tical pipes 116 and lead to a by-pass control valve assembly 120.

This by-pass assembly 120 employs a cylinder 121 with hollow end heads 122 threaded thereon. These heads each have an end 123 and a threaded skirt 124 threaded internally of the cylinder 121. The cylinder 121 has an internal partition 125 with a cylindrical port or opening 126. The pipes 117 have connections to the hollow heads 10 123 as illustrated in Fig. 8.

The adjustable valve plug assembly for the by-pass designated 130 includes a plug 131 which is cylindrical as to its periphery and made substantially the same thickness as the partition 125. This has a close sliding fit in the port 126. Oppositely extending valve stem rods 132 are either formed integral or extend from opposite sides of the plug 131 and have their outer ends each journaled in a sleeve 133, such sleeve being integral with a perforated plate 134. The periphery of the plate is circular and may slide in the cylinder 121, however each plate is maintained in adjusted position by an adjusting screw 135 threaded through an opening 136 in the ends 123 of the hollow heads 122 and has a rotatable neck connection 137 to the end 138 of the sleeve 133, the inner ends of the screws having upset heads. On account of there being two of these perforated plates each with their sleeve 20 and adjusted by the screws 135, these sleeves may be adjusted in the cylinder 121 and as shown in Fig. 8 are in their outermost position in contact with the inner end of the skirt 124 of the hollow heads 122. The valve rods 132 have a sliding motion in the sleeves 133 and are restrained in this motion by compression springs 139 of which there are two coiled on the rods 132 on opposite sides of the plug 131 and engaging the perforated plates 134. These springs when 25 the hydraulic pressure is equalized centers the plug 131 in the port 126 of the partition 125.

In operation, as the lever 51 is forced to one side or the other from its central position, manifestly it moves the piston 30 towards one end of the cylinder 21, thus requiring the transfer of the oil from one end of the cylinder 21 to the other through the by-pass valve assembly 120. The oil flows freely through the perforated plates 134 but on the pressure side meets the resistance of the plug 131 fitting in the opening 126. The pressure however displaces the plug acting against the compression of one of the springs 139 so that the plug is completely displaced from the opening allowing passage of the oil around the periphery of the plug and thence through the communicating pipe 117 and 116 to the opposite end of the cylinder 21. Of course when the plug is being displaced and compressing the spring on one side, the spring on the opposite side urges the movement of the plug in its motion under pressure of the liquid on one face of the plug. When the piston is at the complete end of its stroke or moved as far as the traverse of the cable on the winding drum causes the movement of the piston, as soon as there is equilibrium of pressure in the cylinder, the springs 139 cause the plug 131 to again become centered in the opening 126 and the reverse action takes place when the arm 51 is moved positively in the opposite direction.

70 Various changes may be made in the details of the construction without departing from the spirit or scope of the invention as defined by the appended claims.

I claim:

75 1. A line spooler comprising in combination a

main cylinder having a piston with oppositely directed piston rods connected to the piston and extending through the heads of the cylinder, a cross head connected to each opposite piston rod, a rod connecting the cross heads and reciprocating parallel to the piston, a lever assembly including a lever arm pivoted at a fixed position relative to the cylinder and having a mount at its outer end to engage a cable whereby the lateral movement of the cable oscillates the said arm, a carriage interconnecting the said rod and the lever arm to translate the oscillating movement of the arm to a reciprocating motion of the rod, the cross heads and the piston, a by-pass between opposite ends of the main cylinder including a 10 control valve with a plug and means to restrain the movement of the plug to develop a resisting hydraulic pressure to the movement of the piston and hence the lever arm.

2. A line spooler as claimed in claim 1, the carriage interconnecting the said rod and the lever including a sleeve attached to the rod and having a vertical channel guide, the lever having a pivot bolt connected thereto with an anti-friction bearing operating in the said vertical guide 20 whereby the arcuate oscillating movement and the vertical component of the movement of the bolt develops a vertical sliding motion of the bolt and the anti-friction bearing in the guide channels and the reciprocating motion of the sleeve 25 and the said rod.

3. A line spooler comprising in combination a main hydraulic cylinder having a piston with piston rods reciprocating therein, a by-pass for hydraulic fluid connected to the cylinder at positions always open during the reciprocation of the piston, a pivoted lever assembly having a mount adjacent its free end to engage a cable whereby the lateral movement of the cable oscillates the lever on its pivot, an interconnecting means between the lever and the piston rods to reciprocate said rods and hence the piston during the movement of the lever, the by-pass having a by-pass control valve assembly with a plug and means to regulate the resistance to the movement of the plug and hence the opening action of the valve, the interconnecting means between the lever and the piston rods including a travelling carriage assembly mounted on a rectilinearly moving means connected to the piston rod, said carriage having guides, a pivot bolt connected to the lever and means forming a sliding interconnection between said bolt and the guides of the carriage whereby the oscillating arcuate movement of the lever and bolt communicates a straight line reciprocating motion to the said carriage.

4. A line spooler comprising in combination a main hydraulic cylinder having a piston with piston rods reciprocating therein, a by-pass for hydraulic fluid connected to the cylinder at positions always open during the reciprocation of the piston, a pivoted lever assembly having a mount adjacent its free end to engage a cable whereby the lateral movement of the cable oscillates the lever on its pivot, an interconnecting means between the lever and the piston rods to reciprocate said rods and hence the piston during the movement of the lever, the by-pass having a by-pass control valve assembly with a plug and means to regulate the resistance to the movement of the plug and hence the opening action of the valve, the mount engaging the cable including a pin slidably mounted on the outer end of the lever with a friction means engaging said pin, a plate secured to the pin and a plurality of rollers 75

mounted on the plate to engage the cable on opposite sides thereof, at least one of said rollers being adjustable to vary the pressure and to accommodate changes of size of the cable.

5. A line spooler in which hydraulic liquid is displaced between the ends of a main cylinder through a by-pass comprising in combination a pivoted lever with a connecting means to displace the hydraulic liquid, said lever having an eye on 10 the end, a pin slidably adjustable in said eye with a friction means to retard the movement of the pin, a plate mounted on one end of the pin and rollers to engage a cable rotatably mounted on the said plate.

15. 6. A line spooler as claimed in claim 5, the said plate having a first and second bolt fixed thereon and provided with a slot with a third bolt adjustably mounted in said slot, a first and a 20 second roller rotatably mounted on the first and second bolts on one side of the cable, a third roller rotatably mounted on the third bolt and on the opposite side of the cable whereby the third roller may be adjusted towards and away from the aforesaid first and second rollers.

25. 7. A line spooler as claimed in claim 5, the said friction means including brake shoes attached

to the lever, each shoe having a lining contacting the pin and a clamping bolt engaging the brake shoes to vary the pressure between the lining and the pin.

8. A line spooler in which hydraulic fluid is 5 displaced between the opposite ends of a main cylinder through a by-pass comprising in combination a pivotally mounted lever having an oscillating motion, a carriage having a sleeve attached to a reciprocating means acting on the 10 hydraulic fluid, a channel structure connected to the sleeve, the lever having a pin and an anti-friction bearing mounted on the pin, said anti-friction bearing operating in the channel structure whereby the oscillating movement of the 15 pin by the lever develops a longitudinal motion of the anti-friction bearing in the channel and a reciprocating motion of the sleeve.

9. A line spooler as claimed in claim 8, the 20 anti-friction bearing including an inner ball race mounted on the pin, an outer ball race engaging the channels, such channels having inturned flanges and a series of balls mounted between the inner and outer races.

SAMUEL T. PEPPARD. 25
